PILING MECHANISM FOR PLATE MILLS

Michael J. Ajello, Melvindale, Mich.

Application November 5, 1938, Serial No. 238,953

5 Claims. (Cl. 271—63)

My invention relates to piling mechanism for plate mills, and its principal object is to provide a mechanism whereby the individual plates or sheets, as they issue from the rolls are automatically received and arranged in an orderly pile suitable for transportation from the mill.

Another object of my said invention is to provide a mechanism of the character referred to which is capable of handling even very thin sheets of iron or steel without damage or buckling which are of frequent occurrence when the sheets are handled and piled by hand labor as is customary at the present time.

With these and other objects in view, I will now describe a preferred embodiment of my invention with reference to the accompanying drawing, in which—

Figure 1 is a fragmentary side elevation illustrating an ordinary pair of rolls having my improved piling mechanism arranged in cooperative relation therewith.

Figure 2 is a fragmentary plan view of the same.

Figure 3 is a fragmentary vertical transverse section of the same taken on line 3—3 of Figure 1, and

Figure 4 is an end view of the device shown in Figure 2, looking in the direction of the arrows 4 in the latter mentioned figure.

Like characters designate corresponding parts throughout the several views.

In the drawing, 1 designates a housing of conventional construction having the upper and lower rolls 2, 3, respectively, while 11 indicates any ordinary form of screw down mechanism for regulating the thickness of the plates which the rolls are desired to produce. In front of the rolls are a pair of tables 4, arranged in opposed relation as shown more particularly in Figure 2 of the drawing, and having a series of gaps or openings 41 which extend to their front or opposed edges. Upon the upper surface of the table 4 are provided castors 5 of well known construction which are rotatably mounted upon the several sections of the table and carry wheels or rollers 51, the upper peripheries of which are arranged at such a height as to conveniently receive a plate such as designated P in Figure 1 as it issues from the rolls 2, 3, and intermediate the said rolls are a pair of freely rotatable rollers 31 arranged at the same height as the rollers 51. The size of the table 4 and the number of castors mounted thereupon are arranged to suit the maximum and minimum sizes of plates or sheets which it is desired to produce in this par-

ticular pair of rolls. Beneath the table 4 are two sets of freely rotatable rollers 6 supported upon pairs of girders 61, the inner or adjacent girders of each pair being arranged in spaced relation so as to provide a gap or passage-way 62 therebetween for a purpose to be herein-after explained. The girders 61 are mounted upon piston rods 62' upon the lower ends of which are pistons, not shown, adapted to be moved up and down within the cylinders 63, the movement being effected by any ordinary fluid pressure means, preferably hydraulic, and controlled by appropriate valves and valve operating mechanism which it is not deemed necessary here to describe or illustrate. The tables 4 are supported upon a series of carriages 42, the lower ends of which are provided with truck wheels 43 adapted to travel upon channel-shaped trackways 44 so that they may be moved back and forth towards and away from one another by means of fluid pressure cylinders 45 having therein pistons which are connected by rods 46 to the carriages, as shown in Figure 3.

Within each of the gaps 41 in the tables 4 is a vertical channel-shaped member 47 which projects upwards above the table 4 and serves to maintain the successive plates issuing from the rolls in proper lateral alignment, and in order to adjust these members to suit the particular width of plate to be rolled, the said members 47 are provided with dove-tailed bases 48 which slide in complementary dove-tailed trackways 49 mounted upon the floor surface, and in threaded relation with the bases 48 are right and left hand threaded screw shafts 50 which extend from side to side of the machine, being supported in bearings 51 and are connected by bevel gears 52 and gears 53 to a longitudinal shaft 54 mounted in bearings 55 and provided with the hand wheel 56 by the rotation of which the opposed pairs of members 47 are moved towards and away from each other simultaneously.

Above the tables 4 is a rod 7 suspended by links 71 from any form of overhead support 72', and upon this rod is slidably mounted a downwardly projecting arm 72 which is secured in different positions along the rod as by the set screw 73. The arm 72 is positioned in the path of the plate P as it issues from the rolls 2, 3 so that when the plate in its outward movement reaches a certain position, the rod 7 will be pushed in an outward direction, causing the links 71 to be moved about their pivotal points and thereby operate a switch arm 72' which forms 55

a part of one of the links. In the relative positions of the parts shown in Figure 1, the plate P has just reached the end of its stroke and the switch arm 72' has been moved in position to close a circuit C and energize a solenoid C', causing the plunger C2 to open a valve C3, thereby allowing fluid pressure from a convenient source to pass in the direction of the arrow x through the valve C3 and out in the direction 10 of the arrow y to the cylinders 45, causing the tables 4 to be moved in a direction away from one another, and when these tables have reached the limit of their outward movement, the plate P will be then unsupported by the tables and 15 ready to fall down upon the pile of plates P'. In order, however, to reduce the impact of the plate in falling, the cylinders 63 are furnished with fluid pressure in properly timed relation so as to raise the girders 61 and rollers 6 towards 20 the falling plate.

It will be understood that as the tables 4 move outwards the plates are kept in lateral alignment by means of the guide members 47, and in this manner the sheets fall successively upon the pile 25 in an orderly manner so far as their lateral position is concerned, and in order that they may be similarly disposed in a lengthwise direction, there is provided a vertical arm 8 adjustably mounted upon a bar 81 as by the set screw 82, 30 and as the tables move inwards after discharging the plate P the bar 81 is moved in the direction of the arrow w by means of the cam-like member 84 which is carried upon one of the tables 4 and acts upon the roller 85 which is 35 rotatably mounted upon the bar 81 so that as the tables move inwards the bar 81 is moved as before stated in the direction of the arrow w, so as to bring the newly deposited plate into longitudinal alignment with the plates already 40 in position upon the rollers 6. It will be observed that as the tables move outwards to release another plate, the bar 81 is moved away from the rolls by means of the helical spring 86 which surrounds the reduced portion 87 abutting 45 against the shoulder 88 and reacting against one of the bearings 89 by which the bar is slidably supported. Further, it will be noted that in order to obtain greater precision in controlling the endwise travel of the plate P, one of 50 the links 71 is provided with a stop 74 which limits its movement. Arm 8 is pivoted at 80 so as to fold downwards as at 80' in Fig. 1, allowing plates to pass on to conveyor 611.

It will be observed from the foregoing description and by reference to the drawing that I have provided a simple and effective mechanism for the purpose above recited, and while I have herein described and shown a preferred embodiment of my invention it will be obvious to those skilled 55 in the art to which the same relates that various changes in detail may be made to suit any particular or peculiar requirement without departing from the spirit of my invention as defined in the appended claims. For example, 60 instead of employing fluid pressure means for movement of the various instrumentalities, as herein shown and described, other means such as electric motors may be employed to produce the various movements. It is believed that the 65 valves and other details necessary for actuating the various moving parts in properly timed relation are so well understood that no further description of them is deemed necessary.

Having thus described my said invention, what

I claim and desire to secure by Letters Patent of the United States is:

1. In a mechanism of the character described, the combination, with a pair of rolls, of a pair of horizontally movable tables disposed in equally spaced relation with the vertical center line of said rolls, said tables having a plurality of lateral gaps in their opposed edges; a plurality of castors upon said tables adapted to receive a plate issuing from said rolls; a plurality of pairs of vertical guide members projecting upwardly through said gaps; means for simultaneously adjusting the distance between the respective pairs of guide members to correspond to the width of the plate to be rolled; and means actuated by said issuing plate for moving said tables apart to discharge the same and for returning them to normal position subsequent to such discharge. 10

2. In a mechanism of the character described, the combination, with a pair of rolls, of a pair of horizontally movable tables disposed in equally spaced relation with the vertical center line of said rolls, said tables having a plurality of lateral gaps in their opposed edges; a plurality of castors upon said tables adapted to receive a plate issuing from said rolls; a plurality of pairs of vertical guide members projecting upwardly through said gaps; means for simultaneously adjusting the distance between the respective pairs of guide members to correspond to the width of the plate to be rolled; a series of conveyor rollers beneath said tables; and means actuated by said issuing plate for moving said tables apart to discharge the same upon said 25 rollers and for returning them to normal position subsequent to such discharge. 30

3. In a mechanism of the character described, the combination, with a pair of rolls, of a pair of horizontally movable tables disposed in equally spaced relation with the vertical center line of said rolls, said tables having a plurality of lateral gaps in their opposed edges; a plurality of castors upon said tables adapted to receive a plate issuing from said rolls; a plurality of pairs of vertical guide members projecting upwardly through said gaps; means for simultaneously adjusting the distance between the respective pairs of guide members to correspond to the width of the plate to be rolled; a series of conveyor rollers beneath said tables; means actuated by said issuing plate for moving said tables apart to discharge the same upon said rollers and for returning them to normal position subsequent to such discharge; and means for aligning the plates endwise after each discharge. 35

4. In a mechanism of the character described, the combination, with a pair of rolls, of a pair of horizontally movable tables disposed in equally spaced relation with the vertical center line of said rolls, said tables having a plurality of lateral gaps in their opposed edges; a plurality of castors upon said tables adapted to receive a plate issuing from said rolls; a plurality of pairs of vertical guide members projecting upwardly through said gaps; means for simultaneously adjusting the distance between the respective pairs of guide members to correspond to the width of the plate to be rolled; a series of conveyor rollers beneath said tables; means actuated by said issuing plate for moving said tables apart to discharge the same upon said rollers and for returning them to normal position subsequent to such discharge; and means for aligning the plate endwise after each discharge, said last-named means compris- 40

ing a member movable longitudinally beneath said rollers and having an arm extending upwardly above the pile of plates, and cam means upon one of said tables for actuating said member.

5. In a mechanism of the character described, the combination, with a pair of rolls, of a pair of horizontally movable tables disposed in equally spaced relation with the vertical center line of 10 said rolls, said tables having a plurality of lateral gaps in their opposed edges; a plurality of castors upon said tables adapted to receive a plate issuing from said rolls; a plurality of pairs of vertical guide members projecting up- 15 wardly through said gaps; means for simultane-

ously adjusting the distance between the respective pairs of guide members to correspond to the width of the plate to be rolled; a series of conveyor rollers beneath said tables; means actuated by said issuing plate for moving said tables apart to discharge the same upon said rollers and for returning them to normal position subsequent to such discharge; means for elevating said rollers in timed relation with the outward movement of said tables to receive said plate 10 and for lowering them after such receipt; and means for aligning the plates endwise after each discharge.

MICHAEL J. AJELLO.
